UNITED STATES PATENT OFFICE.

HANS ANDREAS PEDERSEN, OF HADBJERG, NEAR HADSTEN, DENMARK.

LIFTING GEAR FOR BARRELS.

Application filed October 26, 1922. Serial No. 597,190.

To all whom it may concern:

Be it known that I, HANS ANDREAS PEDERSEN, a subject of the King of Denmark, and resident of Hadbjerg, near Hadsten, 5 in the Kingdom of Denmark, have invented new and useful Improvements in Lifting Gears for Barrels, of which the following is a specification.

My invention relates to a lifting-gear for 10 barrels and the like in which a bow-shaped frame forming a support for the barrel to be lifted may be swung upward to lift the barrel by rocking between two sets of uprights and by means of cross-bars engaging 15 with pawls mounted in the said uprights.

When the back-end of the said bow-shaped frame, which is furnished with a handle, is rocked downward, a crossbar at the fore-end is lifted upon higher positioned pawls, while a cross-bar at the back-end is raised, when the handle is swung about the crossbar at the fore-end of the bow-shaped frame.

My invention is illustrated in the accompanying drawings, in which—

Figure 1 shows the lifting-gear in side-view, partly in section,

Fig. 2 shows the same in top-view, and

Fig. 3 shows a modification in side-view.

On a frame consisting for instance of 30 two pieces of I-beams *a* and two pieces of U-beams *b*, are mounted two fixed uprights *c* and two uprights *d*, which latter can be swung about pivots *e*. At the top the uprights *c* and *d* are held in position by means 35 of a hook *f*, mounted on a pivot *g* in the uprights *c* and engaging with a projection *h* on the uprights *d*.

The uprights *c* and *d* can be made of U-beams and are provided with a number of 40 pawls *j* and *k*, turnably mounted on pivots *l* and *m* in the uprights. The pawls *j* and *k* are prevented from swinging downward by backs *n* and *o*.

Between the four uprights a frame is 45 mounted, which for instance consists of two arched bows *p* of I-beams. At the back-ends the bows are connected with a bar *q*, carrying a handle *r*, while the fore-ends, 50 which are rounded, are connected with one another by a stay *t*.

In holes in the lower edges of the bows *p* two cross-bars *u* and *v* are inserted, the ends of which rest on the pawls *j* in the uprights

c and the pawls *k* in the uprights *d*, so that 55 the bows *p* are carried by the cross-bars *u* and *v* and the pawls *j* and *k*.

Each pawl *j* is placed on a level between two opposite pawls *k*.

When a barrel is to be raised, the bar *v* 60 is removed and the bow-shaped frame lowered until the bar *u* rests on the irons *b*, and the fore-ends *s* are resting on the irons *a* as shown in Fig. 1 with dotted lines. The barrel is then rolled over the ends *s* up on 65 the bows *p*. During this operation the uprights *d* can be laid down in a horizontal position.

When thereupon the handle *r* is pressed 70 down, the fore-ends of the bows *p* are lifted up above the lowest pawls *k*, so that the bar *v* may be inserted, whereafter the back-ends of the bows *p* and the bar *u* are, by means of the handle, lifted up over the lowest pawls *j*. The handle *r* is then again 75 pressed down and the bar *v* further lifted and so on.

In this manner the barrel is lifted up 80 slowly by means of the handle *r* that rocks the bows *p* about the bars *u* and *v*, which in passing the pawl *j* or *k* swing these up, whereafter the pawls fall down again. One man can lift a very large barrel, only by moving the handle up and down.

When the barrel has been sufficiently 85 raised, the hooks *f* are released, the handle *r* is lifted up, so that the bar *u* comes out of contact with the pawls *j*, and the bow-shaped frame with the barrel together with the uprights *d* are swung towards the carriage or support, on which the barrel is to be placed, so that it can be rolled up upon the carriage or the support.

The bows *p* and pawls *j* and *k* can be 90 otherwise shaped as shown in the drawings and the pawls may for instance be mounted in the bars *u* and *v* and co-act with teeth on the uprights *c* and *d*, so that the bows *p* in that way are lifted up and with them the barrel.

In the modification in Fig. 3 the lifting 95 bow is formed as a frame *w* for lifting of boxes or the like. The frame *w* is connected with an angular frame *x*, serving for lifting a sack or the like, and furnished with a swingable bow *y* or other means for holding the sack.

By means of the handle *r* the cross-bars *u*

- and v of the frame w can be rocked up the pawls j and k in the described manner. When a sack has been sufficiently raised, a bar z is inserted between the frame x and the uprights d , so that the frame x is prevented from swinging downward, until the sack can be lifted down, or the frame w together with the uprights d be swung about the pivots e .
- 10 By altering the shape of the lifting-frames and by varying the distance between the uprights, my lifting-gear may be adjusted according to all forms for goods, which are to be lifted.
- 15 Having thus described my invention, I claim:
1. In lifting-gears, the combination of a support for goods to be lifted, two sets of uprights enclosing the said support, a number of pawls turnably mounted in the said uprights, a handle firmly connected with the back side of the said support and adapted to be rocked up and down, and two cross-bars placed in the said support and having ends 20 extending over the said pawls and engaging with them, so that the pawls form layers for the said support when rocked up and down

by means of the said handle, substantially as set forth.

2. In lifting-gears, the combination of a support for goods to be lifted, cross-bars 30 removably inserted in the said support and forming pivots, and a handle for rocking the said support up and down about the said pivot, substantially as set forth.

3. In lifting-gears, the combination of uprights, a number of pawls mounted in the said uprights and arranged in rows one above the other, and means for preventing the said pawls from swinging down, 35 substantially as set forth.

4. In lifting-gears, the combination of a supporting frame, a set of uprights firmly mounted in the said frame, another set of uprights swingably mounted in the fore-side of the said frame, and means for holding the swingable uprights in vertical position, substantially as set forth.

In witness whereof I have hereunto set my hand in the presence of two witnesses.

HANS ANDREAS PEDERSEN.
